CLAIM

The ornamental design for a shoe sole, as shown and described.

DESCRIPTION

FIG. 1 is a perspective view of a shoe sole showing my new design;

FIG. 2 is a medial side elevational view thereof;

FIG. 3 is a lateral side elevational view thereof;

FIG. 4 is a front elevational view thereof;

FIG. 5 is a rear elevational view thereof;

FIG. 6 is a magnified view of FIG. 1;

FIG. 7 is a magnified view of FIG. 2;

FIG. 8 is a magnified view of FIG. 3;

FIG. 9 is a magnified view of FIG. 4; and,

FIG. 10 is a magnified view of FIG. 5.

The broken lines in the drawings shoe are for environmental purposes only and form no part of the claimed design.
